UNITED STATES PATENT OFFICE

CHARLES C. ARMSTRONG, OF MARYSVILLE, OHIO.

LOCK OR FASTENING DEVICE FOR HINGED BOX MEMBERS.

1,189,902.

Specification of Letters Patent.

Patented July 4, 1916.

Application filed May 8, 1915. Serial No. 26,841.

To all whom it may concern:

Be it known that I, CHARLES C. ARMSTRONG, a citizen of the United States, residing at Marysville, Ohio, have invented certain new and useful Improvements in Locks or Fastening Devices for Hinged Box Members, of which the following is a specification.

My present invention relates to locks or fastening devices designed more especially for boxes of the type comprising two tray-like members hinged together with an intermediate hinged flap, and the invention includes the novel features of construction and arrangement and combination of parts hereinafter described and defined by the appended claims, an embodiment of the invention being illustrated in the accompanying drawings.

Throughout the specification and drawings like reference characters are employed to indicate corresponding parts.

In the drawings; Figure 1 is a plan view of the tackle box in opened position. Fig. 2 is a sectional view of the box in opened position. Fig. 3 is a sectional view through the lock mechanism showing this mechanism in position which will enable the lock to be opened by pressure when the key is removed. Fig. 4 illustrates the position of the lock mechanism in locked position. Fig. 5 shows details of the lock mechanism, and, Fig. 6 is a sectional view of the tackle box in closed position. Fig. 7 shows details.

In these drawings 1 and 2 comprise the two main members of the box which is shown as representative of my device to which my improved lock or fastening may be applied, each of which is shown in the form of an elongated shallow tray, these two members being hinged together at 3. The member 2 is provided with a turned edge 4 and the member 1 is provided with a flared edge 5 adapted to fit over the turned edge 4, when the member 1 is swung over upon the member 2 as shown in Fig. 6. A leaf or flap 8 is provided hinged about the same axis as the hinged members at 3 and this hinge is preferably formed by projecting ears or portions of the flap or leaf bent around the hinge rod and each of the members 1 and 2 are likewise provided with hinged portions extending around the said rod. The flap or leaf 8 is adapted to cover either member 1, 2 or the box.

My improved locking device is shown as

applied to the box at the point 12 and this, in addition to locking the two main members together, will lock the flap or leaf 8 in position by engaging the opening at 13 formed in said leaf. The wall of this opening at 13' is adapted to engage the notch or shoulder 14 in the catch 15 forming a part of the lock, this catch having an inclined edge at 15' for the edge of the opening at 13' to ride against and spring the leaf or flap laterally in the direction of its plane when it is pressed down over the catch or the catch is pressed into connection with the leaf. A finger opening is provided at 16 by which the user may lift the leaf from the catch, it being necessary for him however, to exert slight pressure laterally or in the direction of the arrow α in Fig. 1 to spring the leaf out of connection with the shoulder 14 of the catch. There is sufficient play or spring of the parts to allow this action to be performed. The lock comprises the catch 15 which consists of a member having its end turned at 16', said catch also having an opening at 17 to permit the insertion of a key. The catch is held by its shoulders at c , and d engaging the walls of a casing e and by a cover plate f held to the casing e by projections g on said casing passing through openings in the cover plate and bent over thereupon. The catch has an opening 18 adapted to engage a projection 19 on the interior of the member 1 and the catch is spring pressed by a leaf spring 20 engaging the catch at its upper and lower ends, the lower end of said spring member being turned back upon itself as shown at 21. This spring member has a central opening the upper and lower edges of which at 22 are bounded by flanges extending up from the body of the plate. This opening is of rectangular form and the flanges or ribs 22 are parallel with each other and afford surfaces against which the bit 23 of the key may work. When the key is turned in the position shown in Fig. 3, the spring is moved downwardly in said figure so that the enlarged portion 21 of the spring member will be moved down outside of the lock casing and when the key is removed the lock can be manipulated to open the box by simply pressing with the finger inwardly upon the key ferrule 24 because with the parts in the position shown in Fig. 3 the spring will yield and allow the catch 15 to be moved inwardly or from the projection 19. The key ferrule 24 is seated in the casing of the lock by its

inner flange engaging a recess in the cover plate *f* and this ferrule is free to turn, it having a slot 25 adapted to receive the key. Now when the key is turned to the position 5 shown in Fig. 4, for setting the lock in retaining or locking position the spring member 20 will be moved to the position shown in said figure with its enlarged end 21 finding a bearing against the inner side of the 10 wall of the casing, as shown at *y* and with the parts in this position the spring at its enlarged end will resist any bodily movement to the left on the part of the catch 15 in Fig. 4 and therefore pressure upon the 15 key ferrule which serves to unlock the parts or release the catch in Fig. 3 will not affect the leftward shifting or springing of the catch 15 in Fig. 4 and therefore the catch will maintain its engagement with the locking lug or projection 19 and the parts will 20 be held together.

It will be seen from the above that in order to unlock the box it is necessary to manipulate the key and also to exert pressure 25 sure of the finger upon the key ferrule axially thereof when the key is removed.

The casing is provided with an opening at *k* to receive the shank or bearing 26 of the key. The spring plate is provided with 30 shoulders to come against the inner side of the casing and limit its throw, and to hold the spring member against dropping out of said casing.

It will be noticed from the above construction 35 that the device can be used as a lock with the key or as a latch without the key.

The box is made of metal throughout and is largely formed of stampings both as to the box structure itself and also as to the 40 lock and latch mechanism.

It will be noticed that the spring member 20 has a hump at 20° and this is borne upon by the turned end 15° of the catch member 15. The purpose of this hump is to 45 restrain the spring member against accidental displacement or prevent it from being jarred out of the position in which it is set by the key. In the position shown in Fig. 3 the end 15° of the catch will bear on the 50 spring on the upper side of the hump and therefore this hump would have to pass by the end 15° in order to make it assume its other position but the spring resistance is such that the parts will be held in the relation shown until the spring is positively operated by the key. In the position shown in Fig. 4, the hump is above the end of the catch and therefore movement of the catch 55 downwardly except when operated positively 60 by the key will be resisted.

What I claim is:-

1. A lock or fastening device for hinged box members having an intermediate hinged leaf, comprising a catch for holding said 65 members and leaf in closed position, said

catch being operable to release said members by pressing it inwardly, and said catch being disengageable from the leaf by springing the latter in a direction at right angles to the direction in which the catch is released to free the two tray like members, substantially as described. 70

2. A lock or fastening device for hinged box members having an intermediate flap comprising a catch for holding said members in closed position, said catch being releasable by pressing it inwardly, said catch having a notch or shoulder on its side edge to engage said flap and having said edge inclined away from said shoulder, said catch 85 also having an opening to receive a locking pin on one of the members, the flap or leaf being slightly movable in the direction of its plane to release itself from the shoulder of the catch, substantially as described. 85

3. A lock or fastening for two members hinged together, a lock for said members comprising a catch on one member and a stud on the other member to be engaged by said catch, a leaf spring pressing upon the 90 catch, a casing containing said catch and leaf spring, said leaf spring having a locking portion to be located between the catch and the casing to prevent the catch from being pushed aside, the said spring having 95 sliding movement in the casing to be removed from control upon the catch and having a portion to be engaged by the key to be moved thereby, substantially as described.

4. A lock or fastening device for two 100 hinged members, comprising a catch on one member, a stud on the other member to be engaged by said catch, a leaf spring for holding the catch yieldingly to its work, said leaf spring being shiftable and when 105 shifted serving to lock the catch against movement and having means to be operated by a key, substantially as described.

5. A lock or fastening device for two 110 hinged members comprising a catch on one member and a stud on the other member to be engaged thereby, a casing for holding said catch, a leaf spring for holding the catch yieldingly to its work, said leaf spring having an enlarged portion for holding the 115 catch unyieldingly to its work, a key ferrule bearing upon the catch to move the same aside when pressure is applied and a key for operating the leaf spring into position to yieldingly hold the catch or to unyieldingly 120 hold the same, substantially as described.

6. A lock or fastening device for two hinged members, comprising a catch on one member and a projection on the other member to be engaged thereby, a leaf spring 125 bearing upon the catch to hold it yieldingly to its work, said leaf spring having a portion to be operated upon by a key and having one end turned back upon itself and to form a rigid stop or backing for the catch 130

when the said leaf spring is shifted into one position and a casing against which said turned end of the spring bears to hold the catch unyieldingly substantially as described.

7. A lock or fastening device for two hinged members, comprising a lock casing, a catch member loosely mounted in said lock casing to have lateral movement while retained against longitudinal movement, a leaf spring in the casing having lengthwise movement and having a portion to be operated upon by a key, a key ferrule which when pressed inwardly will press the catch from engagement with the locking stud, the said leaf spring when in one position as operated by the key allowing the catch to be pushed aside whereas in another position as determined by the key the said leaf spring will obstruct the lateral shifting of the catch, substantially as described.

8. A lock or fastening device for two hinged members, comprising a locking stud on one member, a catch on the other member, a casing containing said catch, said catch having shoulders to abut against the casing to prevent longitudinal movement thereof but allow lateral movement, a leaf spring for pressing the catch yieldingly to its work, said leaf spring having a portion to be operated on by the key and when shifted to locking position by said key obstructing the lateral movement of the catch and its release from the locking stud, substantially as described.

9. A lock or fastening device comprising

two hinged members, one having a locking stud thereon, a casing formed of two members of stamped metal, one having upstanding walls with alining openings in opposite walls and with projecting studs on the other walls and the other member held to the first member by the said studs, said second member being secured to the wall of the box, a catch member having shoulders to engage the walls of the casing to hold it against longitudinal movement while allowing lateral movement within said casing, a spring member bearing on the back face of the catch member, said spring member being shouldered to be stopped by the wall of the casing and having an opening with flanges along the upper and lower margins of said opening against which a key bit may work, said spring member having a turned end to be shifted to and from position between the rear face of the catch member and the wall of the casing to release the said catch member in one position and to lock it in another position against lateral movement and release from the locking projection, a ferrule bearing upon the outer face of the catch member and seated in a depression in the second member of the casing, said ferrule having a key slot, substantially as described.

In testimony whereof, I affix my signature in presence of two witnesses.

CHARLES C. ARMSTRONG.
